TUBULAR NECKTIE KNITTING APPARATUS

Henry Feineman, New York, N. Y.

Application June 2, 1947, Serial No. 751,695

6 Claims. (Cl. 66—57)

1

The present invention relates to circular knitting apparatus, and, particularly, to circular necktie knitting apparatus on which tubular knitted neckties are produced.

Circular necktie knitting apparatus of the character described are, necessarily of small diameter and have but a small circumference providing little space for the arrangement and mounting thereon of pattern wheels and needle actuating cams. As a result of this limitation in space and the number of pattern wheels and needle actuating cams that may be arranged therein, the circular necktie knitting apparatus heretofore in use was limited in the variety of knitting stitches that could be produced thereon, with a consequent restriction and limitation in the patterns and designs of the neckties produced thereon.

More specifically, such knitting apparatus as heretofore used, could carry only two pattern wheels and two needle actuating cams, by reason of the limited space available for mounting the same. Such a combination of wheels and cams could produce only knit and tuck stitches in the knitted fabric produced thereon.

It is the general object of the present invention to provide circular necktie knitting machines for tubular neckties on which a greater variety of knit stitches may be produced, thereby increasing the possible variety in pattern and design of the tubular neckties produced thereon.

It is an object of the present invention to provide cam means that may be conveniently arranged on knitting apparatus of the character described by means of which a selected number of knitting needles may be disposed in welting position, thereby enabling the production of a fabric which may also include welt stitches in addition to the tuck and knit stitches heretofore possible or in place of the tuck stitches.

It is another object of the present invention to provide cam means of the character described which are adaptable for use on any standard tubular necktie knitting apparatus at present in use, without any undue alteration of such apparatus.

It is also an object of the present invention to provide welting cam means for the circular knitting apparatus of the character described which is certain in its operation and highly effective and efficient for its purposes.

It is a further object of the present invention to provide welding cam means for the circular knitting apparatus of the character described which is safe in use and will not interfere with

2

the movement and operation of the knitting needles and will not damage them.

It is a still further object of the present invention to provide welting cam means of the character described which is of relatively simple construction, which it is economical to produce and which it is easy and convenient to install on and remove from the apparatus.

The foregoing and other advantages and 10 superiorities of the apparatus of the present invention will become more readily apparent to those skilled in the art from the embodiment thereof shown in the accompanying drawings and from the description following. It is to be understood, however, that such embodiment is shown by way of illustration only, to make the principles and practice of the invention more readily comprehensible, and without any intent of limiting the invention to the specific details 20 therein shown.

In the drawings:

Fig. 1 is a schematic view, as seen from the top, of a circular necktie knitting apparatus, showing the arrangement of pattern wheels and 25 needle separating cams which control the needles that knit the various types of stitches, including the welting cam of the present invention;

Fig. 2 is a more or less diagrammatic development of the same;

Fig. 3 is a perspective view of one embodiment 30 of a welting cam of the present invention, shown partly in section to show structural details thereof; and

Fig. 4 is a fragmentary plan view of a tubular necktie knitted by the apparatus shown in Figs. 1 and 2, showing, by way of example, welt stitches arranged in diagonal pattern on the necktie fabric.

Referring more specifically to the accompanying drawing, the circular knitting apparatus to which the present invention relates may be of a conventional type, standard in the necktie knitting trade, consisting of a stationary needle cylinder 10, on which are mounted, in the conventional way, knitting needles 11, having latches at their upper ends, and butts 13 adjacent their lower ends. A rotary, annular table 15 is arranged about the cylinder 10.

Mounted on table 15, in the conventional way, are two pattern wheels 16 and 17, respectively, disposed in diametrically opposed position. Associated with each pattern wheel are lifting cam elements 18 and 19, respectively, and stitch cam elements 20 and 21, respectively. The cam surfaces of the lifting and stitch cam elements are

spaced apart, to form the needle butt track or guideway 22.

In the conventional apparatus, as heretofore used, there were provided on the table 15, rectangular, radially disposed recesses 23 and 24, respectively, adjacent each of the pattern wheel positions 16 and 17, respectively, and to the rear of such wheels. The recesses 23 and 24 open into the needle butt track 22, and receive therein cam blocks, such as the cam block 25, having the cam surface end 26 extending into the track 22, and adapted to receive thereon needles selectively positioned by the adjacent pattern wheel to engage upon the cam surface thereof, and be placed in knitting position; the other needles not so selectively positioned being disposed in tucking position.

It will be apparent from the foregoing description that the apparatus to which the present invention relates, as heretofore constituted, could knit only knit and tuck stitches, with a consequent limitation on the patterns and designs that could be produced upon them.

In order to enable the increase in the variety of stitches that could be knit on such apparatus, with a consequent increase in the variety in the patterns and designs of the tubular knitted neckties that could be produced thereon, I have devised means which may engage the needle butts 13 to adjust the needles 11, or a selected number of them, to welting position, thereby enabling the knitting of knit, welt and tuck stitches, or knit and welt stitches, as desired, upon the apparatus.

Such welting means comprises a cam, generally designated as 30, comprising a rectangular body portion or block 31, adapted to fit in the recesses 23 and 24, and to replace therein, in either or both of them, the cam block 25, which is conventionally arranged therein. The cam block 31 may be secured within the respective recess by the same means as the cam block 25, or by any other suitable means, many of which will suggest themselves to anyone skilled in the art.

The block 31 may have mounted on its inwardly facing end 32 a diagonally disposed cam blade 33, arranged at approximately right angles to the tilted adjacent pattern wheel, such as the pattern wheel 16, as shown in the illustrating drawing. The upper end of the blade, which is closest to the pattern wheel, has a forwardly extending, substantially horizontally disposed needle separating lip 34.

It will be readily apparent that a selected number of the jacks on the pattern wheel 16 may be set to raise the butts 13 of a selected number of needles 11, to be engaged on the upper face of the needle separating lip 34 of cam blade 33, so that such selected needles will be normally engaged by the stitch cam element 20; while another selected number of jacks may be set relatively lower, to raise another selected number of needle butts only sufficiently high to be engaged against the lower face of the needle separating lip 34 of the cam blade 33, so that the respective needles will be depressed by the cam blade 33 below the knitting or tucking position, to a welting position.

It will be readily apparent that if only one cam 30 is used on the apparatus, replacing one of the cams 25, a necktie having all three types of stitches in its pattern and design, namely, knit, tuck and welt, will be produced; while if both of the cams 25 are replaced by a cam 30 the knitted necktie will comprise only knit and welt stitches.

In order to avoid the possibility of damage to the needles by the cam blade 33, which is positioned athwart their passage, the blade 33 may be resiliently mounted to be rearwardly displaceable, so that any needle butt striking the edge instead of a surface of the blade will push it rearwardly, out of the way, rather than be damaged thereby.

One form of such blade mounting is shown in 10 the embodiment illustrated in the drawings, wherein the forward end of the cam block 31 is diagonally slotted to receive and guide the blade 33, and to permit its longitudinal movement therewithin. A longitudinal passageway 36 is 15 formed in the cam block 31, extending from end to end, with the outlet 37 therefor, at the rear end of the block 31 being of reduced diameter, to form the interior shoulder 38. To accommodate the rearward movement of the blade 33, the forward upper corner of the block 31 may be entirely cut away, so as not to block the lip 34.

A plunger 39, having the relatively thicker head portion 40, adapted to fit snugly within the passageway 36, is arranged within the passageway 25 36, its opposed end passing through and projecting from the restricted outlet 37. The blade 33 is 30 mounted on the head portion 40 of the plunger 39, and a coil spring 41 is arranged over the plunger 39, intermediate the shoulder 38 and the head 40, to urge the blade 33 resiliently toward the cylinder 10. In order to retain the blade within the track 22, flush with the edges thereof, so that it will not interfere with the movement of the table 15 about the cylinder 10, an adjusting nut 43 is fitted over the threaded projecting end of the plunger 39.

A recess 44 may be formed in the wall of the guideway 22 to permit the rearward movement of the blade 33 when necessary.

40 It will be readily apparent that if any of the needle butts 13 strike the edge of the blade 33, instead of engaging the surfaces thereof, the blade 33 will be pushed out of the way, without damage to the needle, and will return to 45 position upon passage of the needle.

This completes the description of one preferred embodiment of the apparatus and product of the present invention. It will be readily apparent that many modifications and variations thereof may be made by any one skilled in the art, in accordance with the principles of the invention hereinabove set forth and without the use of any inventive ingenuity. I, therefore, desire to be protected for all such variations and modifications that may be made within the spirit of the invention and the scope of the claims hereto appended.

What I claim is:

1. A cam for a tubular necktie knitting apparatus comprising a block having a longitudinal passageway formed therethrough, said passageway having a restricted outlet at one end of the block, a diagonal slot formed in the opposed end of the block and extending laterally from said 60 passageway a distance into the block, a plunger having an enlarged head portion at one end and threads on its opposed end arranged within said passageway with its threaded end projecting outwardly from said restricted outlet, a cam blade 65 secured on the end face of said enlarged head and adapted to fit within said slot, said cam blade having a lip at one end set at an angle to the cam blade, an expansion spring arranged over said plunger within said passageway intermediate the said enlarged head and the inner 70 75

face of said restricted opening, whereby said blade is resiliently urged outwardly of the said slot, and a nut engaging the projecting threaded end of said plunger, whereby the position of the said blade relative the slot may be adjusted, said block having its corner opposite said lip cut away to permit reciprocating movement of the blade within the slot.

2. A cam for tubular necktie knitting apparatus comprising a block having a longitudinal passageway formed therethrough, said passageway having a restricted opening at one end of the block, a slot formed across the entire opposed end of the said block, extending through said passageway, said slot being disposed substantially diagonally across said last named block end, said block having the upper corner thereof that is intersected by said slot cut away, a plunger having an enlarged head portion at one end adapted to fit snugly within the said passageway and having threads on its opposed end arranged within said passageway, its threaded end projecting from said restricted outlet, a cam blade secured on the end face of said enlarged head and adapted to fit within the said slot, said cam blade having a lip at one end set at an angle thereto and arranged to fit in the space formed by said cut-away block portion, an expansion spring arranged over said plunger within said passageway whereby the said blade is resiliently urged outwardly of the said slot, and means engaging the projecting end of the said plunger for adjusting the position of the said blade relative to the slot.

3. A cam for tubular necktie knitting apparatus comprising a substantially rectangular block having a longitudinal passageway formed therein, a diagonal slot formed in one end of said block extending through said passageway and a distance into the block, said slot beginning at approximately a lower corner of the end face thereof and extending upwardly to a point inwardly from the diagonally opposed upper corner of said face, the portion of the block between the upper end of said slot and said upper corner being cut away, a plunger arranged for reciprocating movement within the said passageway, a cam blade mounted on one end of said plunger and adapted to fit within said slot, said blade having a lip at one end thereof set at an angle thereto and adapted to fit within the space formed by said cut-away portion, means for resiliently urging the said blade outwardly of said slot and means for adjusting the position of the said blade relative to the said slot.

4. A cam for a tubular necktie knitting apparatus comprising a block having a longitudinal

passageway formed therethrough and a slot formed in one end thereof extending laterally from said passageway and across said block end, a portion of said end of said block adjacent one end of said slot being cut away, a plunger arranged for reciprocating movement within the said passageway, a cam blade mounted on one end of the said plunger and adapted to fit within the said slot, said blade having a lip at one end thereof set at an angle thereto and adapted to fit within the space formed by said cut-away portion, means for resiliently urging said blade outwardly of said slot and means for adjusting the position of the said blade relative to the said slot.

5. A cam for a tubular necktie knitting apparatus comprising a block having a slot formed in one end thereof extending across the entire end and inwardly thereof, a cam blade having a lip at one end thereof set at an angle thereto arranged in said slot for movement longitudinally of the block, the other end of said blade extending beyond said slot and said block, and means for resiliently resisting the movement of the said blade inwardly of the said slot.

6. A cam for a tubular necktie knitting apparatus comprising a block having a slot formed in one end thereof extending across the entire end and inwardly thereof, a cam blade having a lip at one end thereof set at an angle thereto arranged in said slot for movement longitudinally of the block, the other end of said blade extending beyond said slot and said block, and means for adjustably resiliently resisting the movement of the said blade inwardly of the said slot.
